QUINTIN G. NOBLITT AND EARL C. BOOTH, OF INDIANAPOLIS, INDIANA, ASSIGNORS TO
NOBLITT-SPARKS INDUSTRIES, INC., OF INDIANAPOLIS, INDIANA

ADJUSTABLE DEFLECTOR FOR AUTOMOBILE HEATERS

Application filed March 28, 1930. Serial No. 439,717.

This invention relates to a heating unit particularly for use in connection with automobiles. The said invention relates particularly to the type of heating unit wherein a stream 5 of air to be heated is directed over a heating element. The said heating element is preferably of the hot water type associated with the cooling system of the automobile. Certain features of the invention, however, apply 10 equally to any other suitable type of heating element such as an electrical resistance unit.

The particular feature of the present invention resides in the mounting of a deflector over the face of the heater capable of being 15 rotated to deflect the heated air in any desired direction.

Another feature of the invention resides in the association of shutters forming the deflector for further deflecting the heat in an 20 angular relation to the heating unit in the direction determined by the rotary positioning thereof.

Still another feature of the invention resides in the provision of a suitable handle attached to the deflector for permitting the 25 ready and convenient manual manipulation thereof for rotary positioning.

Still a further feature of the invention resides in the provision of an insulating sleeve 30 mounted in connection with the intake and return pipes for the hot water circulating system wherein it passes through and is secured to the dash board of the vehicle. By this means the tubes are spaced and insulated 35 from the dash board and the attaching members through which they pass. In addition thereto they are yieldingly supported in spaced relation so that vibration will be minimized and heat lost by convection will be 40 reduced.

The full nature of the invention will be more fully understood from the accompanying drawing and the following description and claims:

Fig. 1 is a front elevation of the heater with the deflector mounted thereon. Fig. 2 is a rear elevation of the front face plate of the heater showing the mounting of the deflector on the rear face thereof. Fig. 3 is a central 50 vertical section through the heater and de-

flector. Fig. 4 is an enlarged section taken on the line 4—4 of Fig. 2.

The heater comprises a radiator core 10 supported in an upper header 11 and a lower header 12 connected to the water cooling system of an internal combustion engine mounted in an automobile through the water conduits 13. The radiator core and headers are supported in a suitable casing 14 which is mounted upon the dash board 15 of the automobile by the brackets 16. Supported on the casing at the rear of the heater there is an electric motor 17 operated from the electrical system of the automobile and adapted to drive the fan blades 18 for forcing a current 30 of air through the radiator core from the rear to the front thereof.

The water conduit tubes 13 extend through suitable nipples 19 mounted in the dash board 15 and secured thereto by the nuts 20. 70 Said nipples are provided with an inner recess 21 in which is housed a resilient heat insulating packing sleeve 22. Said packing sleeve which is preferably made of rubber or any other suitable composition is adapted to 75 support the tube free from the inner surface of the nipple so as to be in spaced relation thereto. Thus, the tube is protected from wear and vibration while the convection of heat therefrom is minimized by insulation 80 and the spacing.

Inasmuch as it is desirable to control the direction of flow of the heated air forced through the radiator, there is mounted upon the shield 23 supported upon the front of the radiator casing 24, a deflector 25 having a plurality of pivotally mounted shutters 26 mounted therein. The peripheral edge of the deflector is circular and is provided with the flange 27 extending about the corresponding circular flange 28 defining the opening in the shield 23. The deflector 25 is formed with a rectangular opening having side walls 29 to which the shutters are pivoted. By means 85 of the shutters, the opening in the face of the radiator may be entirely closed, or partially opened as illustrated in the drawing through the medium of said shutters. Furthermore, the shutters may be utilized to deflect the air 90 95 100

at an angle to the axis of the fan and face of the heater.

Inasmuch as it is desirable to deflect the hot air through the medium of the shutters to one side or the other, up or down, the deflector 25 is mounted to rotate upon the shield 23, about the circular flange 28 thereof. For that purpose a handle 30 is provided for permitting the operator to grasp the said handle and rotate the deflector to any desired position.

While being freely rotatable about the shield 23, the deflector is yieldingly held in position thereon through the medium of the spring pressed bolt 31 as illustrated in Figs. 2 and 4. The plate 32 is mounted in position to engage the inner surface of the flange 28 of the shield 23, while the deflector 25 engages the outer surface thereof. Said plate 32 and deflector 25 are then secured together so as to embrace the flange of the shield 23, by the bolt 31, and be spring pressed into yielding engagement through the medium of the spring 33. The plate 32 is interlocked with the deflector 25 by embracing the downward extending flange 34 formed as a continuation of the side wall 29 and extending inwardly therefrom, between the lip 35 and the free edge 36 thereof.

Thus, the deflector with the pivoted shutters mounted thereon is yieldingly held in engagement with the annular flange on the shield 23 so as to be freely rotated thereabout to any desired position of the shutters by means of the handle 30.

35 The invention claimed is:

1. The combination with an automobile heater having an opening through which heated air is discharged, and a shield surrounding said opening, of a deflector associated with said shield, said shield and deflector having cooperative annular bearing surfaces surrounding said opening, and means for yieldingly maintaining said bearing portions in contact for mounting said deflector on said shield while permitting rotative movement therebetween.

2. The combination with an automobile heater having an opening through which heated air is discharged, and a shield surrounding said opening, of a deflector associated with said shield, said shield and deflector having cooperative annular bearing surfaces surrounding said opening, means for yieldingly maintaining said bearing portions in contact for mounting said deflector on said shield while permitting rotative movement therebetween, and an operating handle projecting from said deflector for facilitating the rotary positioning thereof.

3. The combination with an automobile heater having an opening through which heated air is discharged, of a shield surrounding said opening provided with a circular bearing portion, a deflector having a

plurality of pivoted shutters mounted thereon and provided with a cooperative circular bearing portion adapted to engage and bear upon the bearing portion of said shield, and means for yieldingly holding said bearing portions in engagement for supporting said deflector on said shield while permitting rotative movement thereof.

4. The combination with an automobile heater having an opening through which heated air is discharged and a casing mounted thereon, of a circular supporting flange surrounding said opening, a deflector having a rectangular opening therein, a plurality of shutters pivotally mounted in said rectangular opening, said deflector being provided with a circular bearing portion adapted to cooperate with said circular supporting flange and means for holding said bearing portion and supporting flange in contact while permitting rotative movement of said deflector with respect to said heater, whereby said shutters may be turned to any desired angular position.

5. The combination with an automobile heater having an opening through which heated air is discharged and a casing mounted thereon, of a circular supporting flange surrounding said opening, a deflector having a rectangular opening therein, a plurality of shutters pivotally mounted in said rectangular opening, said deflector being provided with a circular bearing portion adapted to cooperate with said circular supporting flange, means for holding said bearing portion and supporting flange in contact while permitting rotative movement of said deflector with respect to said heater, whereby said shutters may be turned to any desired angular position, and a handle projecting from said deflector in position to be grasped by the operator for rotating the same.

6. The combination with an automobile heater having a radiator core, hot water conduits connected to said core for supplying water from the automobile circulating system and returning the same thereto, and a motor driven fan mounted in position with respect to said core to force air therethrough, of a shield mounted about said core and having a substantially circular opening, a circular flange formed about the opening therein, a deflector provided with a circular flange adapted to embrace and bear upon the flange of said shield, said deflector having a rectangular opening, a plurality of shutters pivotally mounted in said rectangular opening, a plurality of clamping plates yieldingly connected with said deflector and extending into embracing engagement with the opposite side of the circular flange of said shield for yieldingly maintaining said deflector in position upon said shield while permitting rotary movement with respect thereto.

7. The combination with an automobile heater having a radiator core, hot water conduits connected to said core for supplying water from the automobile circulating system and returning the same thereto, and a motor driven fan mounted in position with respect to said core to force air therethrough, of a shield mounted about said core and having a substantially circular opening, a circular flange formed about the opening therein, a deflector provided with a circular flange adapted to embrace and bear upon the flange of said shield, said deflector having a rectangular opening, a plurality of shutters pivotally mounted in said rectangular opening, a plurality of clamping plates yieldingly connected with said deflector and extending into embracing engagement with the opposite side of the circular flange of said shield for yieldingly maintaining said deflector in position upon said shield while permitting rotary movement with respect thereto, and a handle projecting outwardly from said deflector for permitting the manual rotary positioning thereof.

8. The combination with an automobile heater having an opening through which heated air is discharged, and a shield surrounding said opening, of a deflector associated with said shield, said deflector having an opening therein, means for varying the area of the opening, and means partially surrounding the opening in said shield for supporting said deflector thereon while permitting rotative movement therebetween.

9. The combination with an automobile heater and a shield having an opening therein, of a deflector associated with said shield, said deflector having an opening therein through which heated air is discharged, means adjustably mounted on said deflector for deflecting the air at different angles relative thereto, and means partially surrounding said deflector for supporting said deflector on said shield while permitting rotative movement thereof.

In witness whereof, we have hereunto affixed our signatures.

QUINTIN G. NOBLITT.
EARL C. BOOTH.
